ORNAMENTAL BUCKLE

John A. Devendor and William A. Devendor,
Jackson Heights, N. Y.Original application July 7, 1933, Serial No.
679,306. Divided and this application October
16, 1933, Serial No. 693,720

7 Claims. (Cl. 41—10)

This invention relates to ornamental buckles adapted to be worn and has for an object to provide a novel buckle comprising a frame and a multiplicity of ornamental buttons or other devices affixed thereto. The invention may be advantageously embodied in an ornamental belt buckle and is illustrated as so embodied.

Other objects and advantages will hereinafter appear.

10 The present application is a division of our pending application, Serial No. 679,306, filed July 7, 1933, for Ornaments.

In the drawings forming part of this specification,

15 Figure 1 is a plan view of a buckle embodying features of the invention;

Figure 2 is a bottom plan view of the structure of Figure 1;

20 Figure 3 is a fragmentary, sectional view taken through one of the buttons of Figure 1;

Figure 4 is a view in elevation, partly broken away, of a buckle tongue having buttons of the kind illustrated in Figure 3 applied thereto;

25 Figure 5 is a bottom plan view of the structure illustrated in Figure 4;

Figure 6 is a view in elevation, partly broken away, of a belt loop having buttons of the type illustrated in Figure 3 incorporated;

30 Figure 7 is a bottom plan view of the structure illustrated in Figure 6; and

Figure 8 is a view, similar to Figure 3, disclosing a portion of a buckle on which a modified form of button is employed.

The belt buckle of Figures 1 to 3 comprises a frame 1 which includes side pieces 2 and 3, end pieces 4 and 5, and a cross bar 6. The side and end pieces include circular enlargements to provide seats or supports for the buttons and the cross bar 6 is notched at the middle to provide 35 a neck portion 7 upon which the buckle tongue may be pivotally mounted. The button 50 comprises a metallic body member 51, a cloth covering 52 therefor and a metallic collet 53. The collet clamps the covering fabric against the 40 downwardly extending flange of the button body 51.

The collet is so constructed that the need for a backing or filling disc is obviated. This result is achieved by making the collet back 45 50 55 in the form of a frustum of a cone. The collet back is provided centrally with an eyelet tube 55. The conical form of the collet back gives an arched effect which prevents the collet from being collapsed when clinching pressure is applied to the eyelet tube. The slope of the col-

let back may be just as illustrated in Figure 3. It is possible, however, to practice the invention in such a way that the collet back is pressed down to a single plane by the upsetting pressure applied to the eyelet tube. So long as the collet back is merely pressed from a convex condition to or toward a flat condition there is no tendency for the collet to release its grip upon the inturned margin of the covering fabric. On the contrary, the grip of the collet upon the fabric is increased. This is quite contrary to the effect which would occur if a collet having a flat back were employed and pressed to a concave condition by the application of the upsetting pressure.

When a collet is employed having the sharp slope illustrated in Figure 3 the frame 1 is desirably provided with a conical recess 56 within which the collet back is received. In any event, however, the frame metal adjacent the opening in which the eyelet tube is received is thinned to facilitate the securement of a good grip by the tube when the latter is upset.

In Figures 4 and 5 buttons 50 of the kind illustrated in Figure 3 are applied to a buckle 25 tongue 86. Since these buttons and the manner of attaching them have already been described no further description of these figures is deemed necessary.

The same thing is true of Figures 6 and 7 30 wherein buttons 50 are shown as applied to a metallic belt retaining loop 87.

The button 18 is illustrated in section in Figure 8. This button comprises a body portion 19 and a collet 20. The collet includes a filler washer 21 which is held in place by collet fingers 22, supporting the collet back, and downturned prongs 23 which are adapted to be clinched outward to lie in an undercut recess 24 at the back of the frame 1.

Buckles and ornaments made up as shown herein of a frame and a multiplicity of buttons may be worked out in a large number of ornamental and attractive designs. The buttons employed may be of any shape and of any suitable 45 materials. They may be covered or uncovered, and if covered various attractive combinations of colors may be combined in the button covers making up a single buckle or ornament. The buttons may be spaced from one another, if 50 desired, but they may be placed so closely together that they form a complete covering for the frame. The frame may be of any desired shape.

We have described what we believe to be the 55

best embodiments of our invention. We do not wish, however, to be confined to the embodiments shown, but what we desire to cover by Letters Patent is set forth in the appended claims.

5 We claim:

1. A one-piece buckle frame comprising a continuous peripheral portion constructed to facilitate the application of a substantially complete covering composed of buttons, and an attaching 10 cross bar, the peripheral portion being composed of a series of button seats each adapted to support, and, to be completely concealed by, a button, and a series of narrow neck portions extending from seat to seat, and each seat portion being provided centrally with an opening adapted 15 for reception of a concealed attaching portion of a button and having a recess at the back for receiving the deformed metal of such attaching portion when the same is clinched.
2. In a tailored buckle, in combination, a frame comprising a peripheral portion formed to provide button seats and fabric covered buttons attached thereto for covering and concealing said peripheral portion, each button comprising a 20 body portion, a flanged collet received within and supported by the body portion, a fabric covering for the body portion having its border portion gripped between the body portion and the collet flange, said collet having a permanently 25 deformable convex back and an eyelet tube at the center of the back, and said frame having openings in which the eyelet tubes are received and having the metal surrounding each opening thinned to provide a space at the back of the 30 frame for receiving the deformed eyelet metal.
3. In a button, in combination, a body portion a fabric covering therefor, and a collet comprising a continuous peripheral flange co-acting 35 with the body portion to grip the fabric covering, an arched convex back extending inward from the flange, and attaching means integral with

the back at the middle thereof and adapted to be deformed by pressure.

4. In a button, in combination, a fabric covered body portion, and a collet having a continuous marginal flange, a permanently deformable arched convex back and attaching means at the middle of the back adapted to be deformed by pressure.

5. In a button, in combination, a body portion, a fabric cover therefor, and a collet having 10 a continuous marginal flange, an arched convex back and an eyelet tube at the middle of the back adapted to be deformed by pressure, said fabric cover being marginally gripped between the body portion and the collet flange.

6. A one-piece buckle frame comprising a continuous peripheral portion constructed to facilitate the application of a substantially complete covering composed of buttons, and an attaching 20 cross bar, the peripheral portion being composed of a series of button seats each adapted to support, and, to be completely concealed by, a button, and a series of narrow neck portions extending from seat to seat, and each seat portion being provided centrally with an opening adapted 25 for reception of a concealed attaching portion of a button.

7. A buckle frame comprising a peripheral portion constructed to facilitate the application of ornamental buttons thereto, said peripheral 30 portion being composed of a series of button seats, each adapted to support a button, and a series of relatively narrow portions connecting the seats, each seat being provided centrally with an opening adapted for reception of a concealed attaching portion of a button and having a recess at the back surrounding said opening for receiving the deformed metal of such attaching portion when the same is clinched.
